(57) CLAIM

The ornamental design for a handbag handle, as shown and described.

DESCRIPTION

Fig. 1.1 is a perspective view of a handbag handle showing the new design;

Fig. 1.2 is a front view thereof;

Fig. 1.3 is a back view thereof;

Fig. 1.4 is a left side view thereof;

Fig. 1.5 is a right side view thereof;

Fig. 1.6 is a top view thereof;

Fig. 1.7 is a bottom view thereof;

Fig. 1.8 is a top view of the handbag handle shown in an alternate configuration with the handbag in an open position; and

Fig. 1.9 is a top view of the handbag handle shown in an alternate configuration with the handbag in a closed position and the handbag handle in an open position.

The broken line showing of the handbag is for the purpose of illustrating environmental structure and forms no part of the claimed design.

1 Claim, 9 Drawing Sheets
